UNITED STATES PATENT OFFICE

2,535,710

CONTROLLER FOR MAGNETIC INDUCTION
ACCELERATORS

Willem F. Westendorp, Schenectady, N. Y., assignor to General Electric Company, a corporation of New York

Application September 25, 1946, Serial No. 699,284

9 Claims. (Cl. 250—27)

1

The present invention relates to apparatus for imparting high energy to charged particles, in particular electrons, by means of magnetic induction effects. The invention is especially applicable in connection with apparatus of the type disclosed in my prior Patent 2,394,071, granted February 5, 1946, to the General Electric Company, a corporation of New York.

Apparatus of the character referred to includes a closed vessel and a magnetic system for producing a time-varying magnetic field which so links the intended orbit of the particles desired to be affected by the apparatus as to induce a field adapted to accelerate the particles in such orbit. A further magnetic field varying concurrently with the accelerating field is created at the locus of the accelerating orbit with such space distribution as to balance the centrifugal tendencies of the particles and to maintain them in the preferred orbit.

It is found that concurrent and conforming variation of the accelerating and restraining fields results in a stable orbit of the accelerated particles as long as the particles remain at low or moderate energy levels. However, as the energy of the particles increases with continuing acceleration, their rate of energy loss due to radiation mounts non-linearly in a manner which progressively destroys the orbital balance and tends to produce deviation of the particles from their desired path before the highest energy levels are attained. This effect has heretofore been considered to impose a limit upon the energy levels attainable by apparatus of the type in question.

It is an object of the present invention to provide means by which the orbit destroying effects attributable to radiation losses may be overcome to a degree which will materially extend the effectiveness of magnetic induction accelerators. In one aspect, the invention includes the provision of means for causing the rate of change of the accelerating field to exceed that of the orbit-restraining field as the accelerated particles approach high energy levels so that the loss of energy by radiation is effectively offset. From another viewpoint, it comprises the provision of an arrangement by which the accelerating and guide fields can be varied concurrently and at the same rate of change throughout a portion of the operating cycle and thereafter caused to vary at different rates throughout the remainder of the cycle.

The features of the invention which I desire to protect herein are pointed out with particularity

2

in the appended claims. The invention itself, together with further objects and advantages thereof, may best be understood by reference to the following specification taken in connection with the accompanying drawings in which Fig. 1 is a partially sectionalized elevation of an accelerator suitably embodying the invention; Fig. 2 is a fragmentary view, partially broken away, which shows in detail some of the features of the discharge vessel of Fig. 1; Fig. 3 is a graphical representation useful in explaining the invention; Fig. 4 is a diagrammatic circuit illustrating in fundamental form one aspect of the invention; Fig. 5 is a further graphical representation; Fig. 6 is a more elaborate circuit diagram which illustrates in detail certain of the features of the invention; Fig. 7 is a further graphical representation explanatory of the operation of Fig. 6; Fig. 8 illustrates an alternative mode of application of the invention, shown schematically; and Fig. 9 is a graphical representation used in explaining Fig. 8.

Referring particularly to Fig. 1, there is shown in section a closed annular glass vessel 10. The space within the vessel provides a circular orbit in which charged particles, specifically electrons, may be accelerated to high energy levels. The vessel is preferably highly evacuated and a high resistance coating, such as an extremely thin layer of silver (not shown) is applied to the inner surface of the wall to prevent wall-charging. Within the vessel 10 there is provided a thermionic cathode 40 (see Fig. 2) which in connection with associated electrodes 41 and 42 serves as a source of electrons to be accelerated. The electrodes 40—42 are supported by a stem 43 and are supplied with energizing potentials by lead-in wires 44 sealed into the stem.

The accelerating mechanism comprises a magnetic structure including an outer rectangular frame 11 of laminated magnetic material. Bridging the upper and lower parts of the magnetic frame at its central region, there is provided a circular core 12 which provides a flux path concentric with the vessel 10 as viewed from above. Annular pole pieces 13 and 14 which have a low reluctance connection 15 with the core 12 are arranged above and below the vessel 10 so as to produce a concentration of flux through the vessel at the locus of the desired orbit of electrons to be accelerated within the vessel. There are provided coils 17 and 18 which surround the pole pieces 13 and 14 and which primarily control the passage of flux through these pole pieces, and there is further provided a coil

20 which surrounds the core 12 and primarily controls the flux through it.

As will be further explained at a later point, means are provided for energizing the coils 17, 18, and 20 to vary the magnetization of the core system above described in a generally sinusoidal fashion. Electrons produced within the discharge vessel 18 are affected in two ways by the variations in magnetic flux thus obtained. In the first place, since the magnetic flux traversing the core 12 links the circular path provided by the vessel, any variations of such flux necessarily produces an electric field tending to accelerate electrons projected along such path. In this latter respect the apparatus is comparable to a transformer with a secondary comprising a circular path along which the various electrons are accelerated. In general, although the voltage per turn in such a transformer may be low, within a practically attainable range of flux variation the electrons can be made to achieve very high energies (several million electron volts) because of the tremendous number of turns which they may execute during a single cycle of magnetic flux variation. In addition to the acceleration produced by flux linking the electron path, the flux produced by the annular pole pieces 13 and 14 in the region (locus) of the electron orbit tends to cause the electrons to follow an inwardly spiraling path. It has been shown that by a proper design of the magnetic structure the centripetal force produced by the magnetic field existing at the electron orbit may be caused to balance the centrifugal tendencies of the accelerated electrons. In general, this result requires that the following relationship be satisfied:

$$\Delta\phi = 2\pi r^2 B_r$$

Where $\Delta\phi$ is the total change in flux included in the electron orbit, r is the radius of the orbit and B_r is the flux density at the orbit. This is referred to as the 2:1 flux relationship. It is readily practicable to design the magnetic structure in such a fashion as to effect the balanced relation of guide field and enclosed flux which is desired for the purpose specified above and which is further necessary for radial and axial stability of the electron orbit. The principles governing the proper space distribution of the guide flux are more fully set forth in D. W. Kerst U. S. patent application Serial No. 445,465, filed June 2, 1942, and assigned to the General Electric Company, a corporation of New York, now matured into U. S. Patent No. 2,394,070.

When all the conditions specified in the foregoing are fulfilled, electrons introduced into the chamber 10 in a period when the magnetic field is increasing may be expected to be drawn into the particular orbit in which a balance of centripetal and centrifugal forces exist and to be continuously accelerated along such orbit as long as the magnetic field increases in value. By this mechanism, electrons may be brought to energy levels on the order of several million electron volts with a continuous balance being maintained between the increasing centrifugal forces operating on the accelerated electrons and the increasing centripetal forces maintained by the constantly increasing magnetic guide field. However, as the higher energy levels are approached, another factor comes into play in that the rate of energy loss of the electrons attributable to electromagnetic radiation tends to increase to a point at which it becomes a significant factor in the equations of motion of the electrons. The result

is, therefore, that the orbital stability initially accomplished by the concurrent growth of the accelerating and guide fields can no longer be maintained and the electrons tend to spiral inwardly toward a point at which they will be intercepted by the structure of the discharge vessel or of the electrode elements within it. Because of this circumstance, it has been suggested that an upper limit is imposed upon the field of usefulness 10 of magnetic induction accelerators. In accordance with my present invention, however, this effect can be overcome in a manner which will now be described.

Several writers have derived substantially the 15 same expression for the energy loss of electrons moving in a circular path in a magnetic field, viz. $5.44 \times 10^{-9} B^4 R^2$ watts per electron, where B is the magnetic field strength, and R the radius of electron gyration, both expressed in M. K. S. units.

20 At the energy levels at which radiation losses become material to the operation of magnetic induction acceleration, the electrons may be considered to have attained substantially the velocity of light, designated by the constant c . We, 25 therefore, may write the time for one revolution of a given electron as

$$\frac{2\pi R}{c}$$

30 Combining this expression with the expression given above for radiation energy loss and recognizing watts per electron as being equivalent to joules per second per electron, we may express the loss per electron as

$$35 5.44 \times 10^{-9} B^4 R^2 \times \frac{2\pi R}{c} \text{ joules/revolution}$$

But electronic energy measured in joules is also expressible as eV where e is the electronic charge 40 in M. K. S. units and V is the accelerating potential in volts. We may, therefore, say that the energy loss per revolution attributable to radiation is equivalent to a decrease in accelerating voltage determined by the following equation:

$$45 V = \frac{5.44 \times 10^{-9} B^4 R^2 \times 2\pi}{c \times e} \text{ (in M. K. S. units)}$$

Substituting the known values of the various constants, we have

$$50 V_{(\text{loss per revolution})} = 712 B^4 R^3 \text{ (in M. K. S. units)}$$

This interpretation of the nature of the losses attributable to radiation at high energy levels offers the possibility of offsetting such losses by introducing into the accelerating system a corrective voltage V_c which increases at a rate corresponding to the rate of increase of the loss function. In Fig. 3 the introduction of such a corrective voltage is indicated by superimposing on the normal sinusoidal accelerating flux ϕ_n produced through the central core 12 of the accelerator of Fig. 1 a corrective flux ϕ_c adapted to produce a corrective accelerating voltage of the desired magnitude. The production of this corrective flux assumes the induction in the coil by which the flux is produced of a corrective voltage V_c which is shown as being superimposed upon the normal voltage function V_n . My invention is concerned in large part with the provision of 60 means for suitably applying the corrective voltage V_c .

Any attempt to employ the foregoing analysis in overcoming the difficulties attributable to radiation losses requires consideration of the fact that 75 the increased rate of growth of the accelerating

flux, which appears to be required as high energy levels are approached, must be an increase relative to the rate of growth of the guide flux. That is to say, enhancement of the accelerating flux must occur without a corresponding enhancement of the guide flux in order that the forces tending to produce outward motion of the accelerated electrons may not be offset by a corresponding increase in the strength of the centripetal force exerted by the guide field. This presupposes, therefore, that the strengths of the accelerating and guide fields may be independently controlled while maintaining them wholly synchronized and co-ordinated as far as their normal rate of growth is concerned.

An approximation to the ideal form of radiation compensation visualized in Fig. 3 may be produced on a basis consistent with the foregoing requirement by a circuit arrangement such as that shown in Fig. 4. In this circuit the coils 17, 18 correspond to the correspondingly numbered guide field coils of Fig. 1, and the coil 20 corresponds to the accelerating coil of Fig. 1. The coils are connected in a parallel resonant circuit which includes coils 17, 18 in one of its branches and the coil 20 in series with a capacitor 30 in its other branch. Power is supplied to the various coils by means of a transformer having a multiterminal secondary winding 32 and a primary winding 33 which is assumed to be connected to a suitable power source such as a 60 cycle supply (not shown). The common point of the coils 17, 18 and of the capacitor 30 is connected to a terminal 35 of the transformer winding 32, which terminal is indicated as being variable for purposes of permitting adjustment of the electron orbit as controlled by the potential applied to the coils 17, 18. A second transformer terminal 31 is connected to the common point 38 of the coils 17, 18 and the coil 20 through an electronic circuit including controlled gaseous discharge tubes 45 and 46 the function of which will shortly be described. A third transformer terminal 48 intermediate in potential between the terminals 35 and 37 connects to the common point 49 of the coil 20 and the capacitor 30.

Assuming the discharge devices 45, 46 to establish an effective conductive connection between the terminal 37 and the point 38, as they will later be shown to do, the characteristics of the circuit described are such that the relationship between the guide field produced by the coils 17, 18 and the accelerating flux produced by the coil 20 may be definitely fixed by properly selecting the ratio of turns of the transformer sections 35—48 and 48—37 to produce the aforementioned 2:1 flux relationship. For present purposes, the two guide coils have together substantially the same number of turns as the accelerating coil and are connected in bucking relation with it in series with the capacitor 30. By excitation derived from the supply transformer 32, sinusoidal oscillatory currents are set up in the series circuit consisting of the accelerating coil 20, the guide coils 17, 18 and the capacitor 30. Since the pole pieces 13 and 14 of Fig. 1 are encircled only by the coils 17 and 18, the flow of currents in these coils will establish a guide flux between the pole pieces. However, since the central core 12 links both the coils 17, 18 and the coil 20 and since these coils are in bucking arrangement, no flux will be produced in the core by the oscillatory currents referred to. Conversely, any flux produced in the core 12 by a voltage separately applied to the terminals of the coil 20 will induce an equal and

opposite potential in the coils 17 and 18 and will thus prevent current flow in such coils attributable to the application of such voltage. Accordingly, voltage separately applied to the coil 20 will affect the accelerating flux in the core 12 without modifying the guide flux produced between the pole pieces 13 and 14 by the coils 17, 18. Means for applying such a voltage in a way which will maintain the desired 2:1 flux relationship above referred to and at the same time produce an accelerating flux calculated to offset energy losses attributable to radiation are described in the following.

It is hardly practical (although not theoretically impossible) to produce through the central core 12 a compensating flux in exact accordance with the time function indicated by the shaded area ϕ_c of Fig. 3. However, an adequate approximation can be obtained by means of the circuit elements shown at the upper right-hand corner of Fig. 4. Specifically, there is illustrated a controlled gaseous discharge tube 55 which is connected between the resonant circuit point 38 and a terminal 56 of the transformer winding 32 which is relatively higher in potential with respect to terminals 35 and 48 than is the terminal 37. The control element 58 of the discharge tube 55 is assumed to be so energized as to render the tube conductive at a point in the operating cycle of the apparatus as a whole at which radiation losses have become significant. Assuming a lagging current to be flowing at this time from the transformer 32 through the tube 46 and into the coil 20 (as will be the case in the normal operation of the equipment), the act of rendering the tube 55 conductive will cause current flow to commutate to that tube (i. e., by causing cessation of conduction in tube 46) with the result that an increased voltage will immediately be impressed across coil 20. The magnitude of this increase will be that of the potential difference between the terminals 37 and 56 and may be made of any value considered necessary to produce the desired radiation compensation. Because of the bucking arrangement of the accelerating and guide coils described above, the increase in the flux produced by coil 20 will develop in the coils 17 and 18 an induced voltage equal and opposite to the increase in the total voltage applied between the circuit points 38 and 49 so that no change in guide field flux will occur. It can be proven that for the attainment of this ideal condition the coils 17, 18 should aggregate slightly more turns than the coil 20; this being attributable to the finite reluctance of the return magnetic path through the yokes and legs of the magnetic frame 11. If zero reluctance of this path could be realized, an equal number of turns in the guide coils and accelerating coils would be indicated.

The effect of the operation of the circuit arrangement just described is illustrated graphically in Fig. 5, which is to be compared with the ideal conditions assumed in Fig. 3. As will be seen, the functioning of the discharge tube 55 at a time t_1 imposes upon the voltages V_{n_1} normally applied to the accelerating coils 20 a pulse of corrective voltage V_{c_1} which may initially be in excess of the ideal value but which in time assumes a level below the ideal value, the average result being not far from that considered ideally desirable. In terms of flux change, the effect of the operation of the discharge tube 55 is represented by the shaded area ϕ_{c_1} superimposed upon the normal flux curve ϕ_n .

While the result obtained in accordance with

Fig. 5 may seem an unduly coarse approximation of that indicated as desirable in Fig. 3, a relatively large tolerance is permissible in view of the fact that the electron energy is determined not by the instantaneous voltage per turn but by its integral from the moment of injection, that is to say, by the flux within the orbit. If the total flux encircled at a particular moment is a few percent lower than what it should be in order to maintain the proper orbit diameter, the orbit diameter will shrink by an approximately corresponding percentage, but unless a relatively large departure is involved, this will not result in interception of the electrons.

Fig. 6 illustrates in somewhat more complete detail circuit arrangements by which results of the character outlined in the foregoing are obtained. In this figure, elements corresponding to items previously described in connection with Figs. 1 and 4 bear identical numerals. In accordance with the arrangement previously outlined, a transformer having a secondary winding 32 supplies energy to a resonant circuit comprising an accelerating coil 20, guide coils 17, 18 and a capacitor 39. An annular discharge vessel 10 is provided in such relation to the magnetic structure served by the coils (see Fig. 1) as to permit electrons released within the vessel to be accelerated to high energy levels in a circular orbit. Injection of electrons at an appropriate point in the operating cycle is accomplished by means of a winding 60 inductively coupled to the coil 17 and connected to the accelerating electrodes (not shown) of the device 10 through a timing circuit indicated diagrammatically by the block outline 62. The winding 60 and the timing circuit 62 are preferably of the character described in my prior Patent 2,394,071 previously referred to herein. The coil 20 is connected to terminal 37 of the transformer winding 32 through a circuit which includes controlled gaseous discharge devices 45 and 46 connected in back-to-back relationship so as to be conductive during predetermined portions of the opposite halves of the operating cycle. Additional tubes 55 and 65 provide means for alternatively connecting coil 20 to transformer terminals 56 and 67 in accordance with a mode of operation to be explained in the following.

The operation of the circuit so far described may best be understood by reference to the graphical representations of Fig. 7 in which the upper curve V may be taken to represent the voltage appearing across the coil 20 of the accelerating apparatus. The curve I represents the magnetizing current through the coil 20 as supplied through the transformer winding 32, and the curve ϕ represents the flux which links the electron orbit within the vessel 10 as the result of current flowing in the coil 20. The displacement between the curves of current and flux is explainable as the result of losses occurring in the magnetizing circuit.

In order that the tubes 45, 46, 55 and 65 may each be rendered conductive at the desired points in the operating cycle of the apparatus, they are respectively connected through appropriate circuits to an auxiliary transformer winding 69 inductively coupled to the winding 32 (e. g., a winding upon the same transformer core). This connection assures synchronization between the grid control of the various tubes and the alternations of the exciting current supplied to the various coils of the accelerating apparatus. In the case of the tube 46, connection

of its grid 46' to the auxiliary supply source 69 is through a coupling transformer 71 connected in such fashion that the tube 46 is automatically rendered conductive during the positive portion 5 of the cycle, thus permitting current of the indicated polarity to flow to the coils during this portion of the cycle. The tube 45, on the other hand, has its grid 45' reversely connected through a transformer 72 so that it is automatically conductive during the negative portion 10 of the voltage wave. The electron injecting circuit provided by the combination of the winding 60 and of the timing circuit 62 is so adjusted as to cause electrons to be injected 15 into the discharge vessel 10 at or near the point t_1 at which the flux wave ϕ (Fig. 7) passes through zero value. Accordingly, acceleration of the electrons thus induced occurs as the flux continues to increase due to continued flow of current 20 through the exciting coils.

The flux continues to increase along a sinusoidal curve until a time t_2 at which it is assumed that the effect at the electron orbit of energy losses attributable to radiation is beginning to become significant. At this point it is desired to render the tube 55 abruptly conductive so that the voltage applied to the coil 20 may be suddenly increased by connecting the coil 25 through the tube to the transformer terminal 55. To accomplish this result, there is provided in connection with the grid 55' of the tube 55 a timing circuit connected between the grid and the auxiliary voltage source 69. This circuit includes a conventional phase shifting network 30 including a reactor 75 having serially connected across it a resistor 76 and a capacitor 77. Terminals 78 and 79 are respectively provided at the midpoint of the reactor 75 and at the junction point of the resistor 76 and the capacitor 40 77, the phase of the voltage between these terminals being determined by the relative impedance values of the resistor and the capacitor in accordance with principles well understood in the art. For present purposes, the adjustment is 45 such as to produce a lag on the order of 60° between the voltage of the source 69 and that appearing at the terminals 78 and 79. This phase-retarded voltage is applied to the primary of a peaking transformer 82 having its secondary 50 connected directly in the grid circuit of the tube 55. A biasing battery 84 connected in this grid circuit assures that the tube 55 shall not become conductive until a pulse of peaked voltage is delivered by the transformer 82 in 55 accordance with its peaking characteristics.

Upon application of a voltage pulse to the grid 55' of the tube 55 through attainment of the proper level of the voltage applied to the transformer 82, the tube becomes conductive, thus establishing a circuit between the coil 20 and the transformer terminal 56. The voltage then existing across the parallel circuit including the tube 46 can be shown to be in such direction as to cause extinction of this tube with resultant commutation of the current to the coil 20 to the tube 55. This operation, which is assumed to occur 60 at the time t_2 (Fig. 7), results in an abrupt increase in the voltage applied to the coil 20, as indicated at V_{C_1} . A corresponding increase I_{C_1} will be occasioned in the magnetizing current and this in turn will lead to enhancement ϕ_{C_1} of the flux produced in the central core of the magnetizing structure.

In order more closely to approximate the ideal wave form of the compensating flux required to

offset radiation losses (as indicated, for example, in Fig. 3), a second enhancement of the flux is accomplished at a slightly later time by the action of the tube 65. Like the tube 55, this tube is controlled by the action of a phase shifting circuit which, in this case, includes a reactor 90 and the series combination of a resistor 91 and a capacitor 92. Terminals 93 and 94 are provided in connection with this network from which a voltage is derived for application to a peaking transformer 96 which is connected to the grid 65' of the tube 65. A battery 97 connected in circuit with the grid 65' assures that the tube 65 shall not be rendered conductive until a favorable voltage pulse is delivered by the transformer 96. The adjustment of the impedance values of the phase shifting network 90, 91, 92 is such as to cause the tube 65 to be triggered at a time t_3 (Fig. 7) which follows by a definite interval the triggering of the tube 55.

At the time t_3 the tube 65 functions to establish a conductive connection between the coil 20 and the transformer terminal 67, resulting in a further voltage increase V_{c_2} in the potential applied to the coil 20. This results in a change I_{c_2} in the current flowing in the coil which in turn augments the accelerating flux by an amount ϕ_{c_2} . It is to be noted that current flow is commutated from the tube 55 to the tube 65 in accordance with a mode of operation previously explained. If desired, a ballast circuit including a resistor 99 and a condenser 100 may be placed in circuit with the tube 65 as shown so as to limit the current drawn from the transformer 32. The condenser 100 has the further function of assisting commutation of current control back to the tubes 45 and 46 as the voltage V (Fig. 7) passes through zero. As has been previously explained, the tube 45 is connected so as to become conductive at the time of voltage reversal.

The functioning of the apparatus described in the foregoing results at the appropriate point in the operating cycle in an increase in the accelerating flux (i. e., the flux through the core 12) as contrasted with the guide flux produced at the locus of the electron orbit. This in turn prevents the inward spiraling of electrons which would otherwise result because of energy losses attributable to radiation and in effect maintains the electrons in a stable orbit for a longer accelerating period than would otherwise be realized. This permits the total energy of the electrons to be brought to a higher level than would appear to be theoretically possible in view of the limitations heretofore thought to be imposed by the radiation problem.

Ultimate diversion of the electrons may be accomplished by the provision of pulse operated orbit shifting means of the character described in G. C. Baldwin Patent 2,331,788, granted October 12, 1943, or alternatively of the character described in my prior Patent 2,394,072, granted February 5, 1946. Since such means forms no material part of my present invention, it does not require to be described in detail herein. Very generally, however, it may include auxiliary coils for superimposing an orbit diverting field upon the main field of the magnetic structure, together with appropriate circuits for abruptly energizing such auxiliary coils at a desired point in the accelerating cycle. Upon operation of the orbit diverting means, the diverted electrons may be intercepted by a target (not shown) appropriately provided in the discharge vessel, or other means may be employed to assure that the accelerated

electrons produce radiation or other effects which can be usefully employed outside the discharge vessel.

In a preferred embodiment the invention may be usefully combined with D.-C. biasing provisions of the type described and claimed in my prior application Serial No. 616,634, filed September 15, 1945, and assigned to the same assignee as the present application. An arrangement serving this purpose is illustrated in Fig. 8. In this figure only the magnetizing circuits are shown, it being assumed that the accelerating vessel and the magnetic structure are identical with those described in connection with Fig. 1.

In Fig. 8 there are shown guide field coils 110 and 111 connected in bucking relation to an accelerating coil 112 which with a capacitor 113 completes a parallel resonant circuit. The exciting circuit for the resonant system includes a transformer having a primary or input winding 115 and a secondary winding 116 which is provided with a number of appropriately displaced terminals 117 to 121, inclusive. The potential occurring between the terminals 117 and 118 is connected to the resonant circuit capacitor 113 through a blocking capacitor 125, the function of which will shortly appear. The terminal 117 involves an adjustable tap arrangement which can be used to fix the relationship between the total excitation of the coils 110, 111 and the coil 112 so as properly to locate and stabilize the orbit of the electrons desired to be accelerated. The coil 112 connects at one end to the transformer terminal 118 through the blocking capacitor 125 and at its other end may be variously connected to the terminals 119, 120 and 121 through controllable discharge tubes 127 to 130. The bucking connection of the coil 112 with respect to the coils 110 and 111 means that changes in the potential applied to the coil 112 will be reflected only in a change in the accelerating flux produced through the central core of the magnetic structure and will be inductively cancelled as far as the circuit which includes the coils 110 and 111 is concerned. Therefore, no change in the guide field controlled by the latter coils will be occasioned by a change in voltage across coil 112. Accordingly, increasing the potential applied to the coil 112 by sequential energization of the tubes 128 to 130 in the order specified will permit an increase in the relative magnitude of the accelerating flux to be effected in accordance with principles previously described herein. This will offset the effects of losses attributable to radiation as the accelerated electrons approach high energy levels.

As has been shown in my prior application Serial No. 616,634, above referred to, the power losses in a magnetic accelerator of given dimensions may be appreciably reduced and the operating range of the accelerator correspondingly extended by superimposing upon the alternating guide field a unidirectional field of appropriate magnitude. The nature of the indicated superposition is illustrated graphically in Fig. 9 which shows how a D.-C. field of magnitude A may be employed to shift the axis of flux reversal from the dotted line position Y_0 to the position Y_1 . With this change, the total growth in field which may be realized from the time of its reversal from the negative to the positive direction (i. e., at the point X_1) to its attainment of maximum value at point X_2 is obviously materially greater than that realizable between X_3 , the point of reversal in the absence of bias, and X_2 . In effect,

11

the resulting asymmetric alternating magnetic field rises from a new zero value indicated by the solid base line Y₁. If the injection of the electrons is timed to occur near the zero field value, that is, at X₁, the total period during which the electrons can be affected by a constantly increasing guide field is obviously materially extended.

Asymmetric magnetization is desirable only at the locus of electron orbit (i.e., only in the guide field). The only requirement for the flux passing through the electron orbit is that its total change from the instant of zero field intensity at the orbit fulfill the 2 to 1 relation:

$$\Delta\phi = 2\pi R^2 B$$

It will be noted that $\Delta\phi$ remains positive provided ϕ is changing along a curve of positive slope even though the flux is negative at the instant from which $\Delta\phi$ is measured. This suggests that as far as the accelerating flux is concerned the use of a unidirectional component to assure a longer period of positive flux is unnecessary. Moreover, it is definitely undesirable because it may cause premature saturation of the magnetic core when added to the alternating flux. From another viewpoint, the use of a unidirectional flux component through the core which passes the accelerating flux may require the core to be larger than would otherwise be necessary in order to avoid premature saturation.

It is found that in connection with a structural arrangement such as that of Fig. 1, the objective of producing a unidirectional flux component in the guide field area without concurrently producing such a component through the central magnetic core may be accomplished by the arrangements indicated in Fig. 8. As illustrated, a source of D.-C. potential 135 is connected in parallel circuit with the resonant circuit capacitor 113, a choke reactor 136 being connected in series with the D.-C. source in order to prevent unwanted A.-C. currents from flowing through the latter. A capacitor 137 which shunts the D.-C. source 135 permits the flow of the necessary magnetizing current for the reactor 136 without requiring that such current pass through the D.-C. supply source. The blocking condenser 125, previously referred to, prevents D.-C. current from reaching the transformer 116.

As a result of the bucking connection of the coil 112 with respect to the coils 110 and 111, the D.-C. current flowing through these coils is essentially self-neutralizing as far as its magnetizing effect upon the central core of the magnetic structure is concerned. That is to say, the magnetizing effect in one direction attributable to the coil 112 is offset by the equal magnetizing effect in the other direction of the coils 110 and 111.

This is not the case, however, with respect to flux produced in the guide field region, which is outside the coil 112 (see the construction of Fig. 1). The effect of the D.-C. current flowing in the coils 110 and 111 is, therefore, not neutralized as far as the guide field is concerned and the desired unidirectional biasing of this guide field in accordance with the graphical representation of Fig. 9 is obtained. The net result, therefore, is that the advantages in terms of decreased power requirements and diminished size of equipment attributable to this feature are usefully combined with the means previously described for compensating radiation losses.

It can be shown that for the ideal condition of zero unidirectional flux through the central core,

12

the guide coils 110 and 111 should aggregate slightly more turns than the coil 112, this being caused by differences in the magnetic paths involved with respect to the two coils. With exactly this same turn ratio, any rate of change of flux present in the central core will produce equal voltages in the two sets of coils, thus assuring the desired absence of any reaction upon the guide field of the compensating flux produced from time to time through altering the energization of the coil 112.

Disturbance of the electron orbit may be accomplished when the desired degree of electron acceleration has been attained by pulse-operated orbit-shifting means of the type previously referred to herein.

While the means described in the foregoing for introducing compensating voltages to offset radiation losses do not realize the ideal curve of compensation as illustrated, for example, in Fig. 3, the closeness of the approximation can be materially improved by increasing the number of voltage steps included in the compensating circuit. Alternatively, it is entirely possible by means of electronic circuits of refined design (well within the present knowledge of the electronics art) to provide in a separate source a compensating voltage having a wave form corresponding precisely to the ideal wave shape. As a practical matter, however, the arrangements shown herein represent a sufficient improvement over what can be realized in the absence of compensation to be considered adequate for all practical purposes and to obviate the need for a more elaborate approach.

What I claim as new and desire to secure by Letters Patent of the United States, is:

1. A magnetic induction accelerator comprising a source of charged particles, means in proximity to said source for projecting the particles along a desired path, electromagnetic means in intimate inductive relation with said path for subjecting charged particles to an increasing magnetic flux whereby such particles are accelerated, and energy-supplying means forming a part of said electromagnetic means and operative after predetermined acceleration of said particles to increase the rate of change of said flux, thereby to compensate for radiation losses occurring as said particles attain high energy levels.

2. Apparatus having means by which charged particles may be accelerated comprising a source of charged particles, means in proximity to said source for projecting the particles along a desired path, electromagnetic means inductively coupled with said path for producing a changing magnetic guide field for confining such particles to an orbital path in spite of increases in the energy of said particles, and electromagnetic means in intimate inductive relation with said path for producing a changing magnetic flux linking said path in order to induce acceleration of said particles, the rate of change of said flux being similar to the rate of change of the guide field over an initial period and being greater than such rate of change over a second period in order to offset radiation losses of the accelerated particles.

3. Apparatus having means by which charged particles may be accelerated along an orbital path, electromagnetic means in intimate inductive relation with said path for producing a magnetic field in the locus of said path which increases at a predetermined rate, electromagnetic means inductively coupled with said path for

producing magnetic flux which links said path and which varies over an initial period at a rate similar to the rate of increase of said field, whereby said particles are maintained in said path by said field in spite of acceleration caused by said flux, and energy-supplying means forming a part of said electromagnetic means and operative to selectively increase the rate of change of said flux after said particles have attained substantial energy, thereby to offset radiation losses tending to cause premature deviation of said particles from said orbital path.

4. Apparatus in which charged particles are to be accelerated along an orbital path, comprising: a coil inductively coupled to said path tending when energized to produce a magnetic guide field in the locus of said path and a magnetic flux linking the path, a second coil inductively coupled to said path primarily for producing a flux which centrally links said path, said coils being in bucking relation with respect to voltages induced by flux which links the path, energy-supplying means for increasing the excitation of said coils at similar rates during an initial period to accelerate charged particles along said orbital path while maintaining them in said path by the action of said guide field, and energy-supplying means for increasing the excitation of said second coil with respect to said first coil at a predetermined point in the operating cycle thereby to prevent unwanted deviation of said particles from said path because of energy losses attributable to radiation.

5. Apparatus in which charged particles are to be accelerated along an orbital path, comprising: a coil in intimate inductive relation with said path and tending when energized to produce a magnetic guide field in the locus of said path and a magnetic flux linking the path, a second coil in intimate inductive relation with said path primarily for producing an accelerating flux which centrally links said path, said coils being in bucking relation with respect to voltages induced by flux which links the path, energy-supplying means for increasing the excitation of said coils at similar rates during an initial period to accelerate charged particles along said orbital path while maintaining them in said path by the action of said guide field, and electronic switching means in circuit with said second coil for selectively increasing the excitation of said coil with respect to said first coil at a predetermined point in the operating cycle thereby to offset the effect of energy losses attributable to electromagnetic radiation by said particles.

6. Apparatus in which charged particles are to be accelerated along an orbital path, comprising: a coil in intimate inductive relation with said path tending when energized to produce a magnetic guide field in the locus of said path and a magnetic flux linking said path, a second coil in intimate inductive relation with said path primarily for producing an accelerating flux which links said path, said coils being in bucking relation with respect to voltages induced by flux which links said path, a parallel resonant circuit including said first coil in one branch thereof and a capacitor in series with said second coil in the other branch thereof, a source of potential for exciting said resonant circuit at its proper frequency, said source having a plurality of terminals of varying potential difference, a connection between a terminal of said source and a point common to said first coil and said capacitor, a connection between the common point of said

first and second coils and a terminal of said source which is at a desired potential difference with respect to said first terminal, a connection between a point common to said second coil and said capacitor and a terminal of said source intermediate in potential between said first and second terminals, and means operative at a predetermined time in the operating cycle to shift the connection of said second mentioned point to a terminal of said source having a higher potential difference with respect to said first and third terminals than does said second terminal.

7. Apparatus in which charged particles are to be accelerated along an orbital path, a coil in intimate inductive relation with said path tending when energized to produce a magnetic guide field in the locus of said path and a magnetic flux linking said path, a second coil in intimate inductive relation with said path primarily for producing an accelerating flux which links said path, said coils being in bucking relation with respect to voltages induced by flux which links said path, a parallel resonant circuit including said first coil in one branch thereof and a capacitor in series with said second coil in the other branch thereof, a source of potential for exciting said resonant circuit at its proper frequency, said source having a plurality of terminals of varying potential difference, a connection between a terminal of said source and a point common to said first coil and said capacitor, a connection between the common point of said first and second coils and a terminal of said source which is at a desired potential difference with respect to said first terminal, a connection between a point common to said second coil and said capacitor and a terminal of said source intermediate in potential between said first and second terminals, and an electronic switching circuit actuatable at a predetermined time in the operating cycle to shift the connection of said second mentioned point to a terminal of said source having a higher potential difference with respect to said first and third terminals than does said second terminal, whereby the flux linking said path is increased with respect to the field at the locus of the path in order to compensate for radiation losses occurring as the accelerated particles reach high energy levels.

8. Apparatus in which charged particles are to be accelerated along an orbital path, comprising: electromagnetic means inductively coupled to said path for producing in linkage with said orbital path a symmetrical alternating magnetic flux for inducing acceleration of said particles, electromagnetic means inductively coupled to said path for producing in the locus of the path an asymmetric alternating magnetic field serving to maintain said particles in said path, the rates of change of said flux and said field being initially correlated, and energy-supplying means forming a part of said electromagnetic means and operative at a predetermined point in the operating cycle to selectively increase the rate of change of said flux to compensate for losses attributable to electromagnetic radiation as said particles attain high energy levels.

9. In apparatus in which charged particles are to be accelerated along an orbital path, a coil in intimate inductive relation with said path and tending when energized to produce a magnetic guide field in the locus of said path and a further flux centrally linking said path, a second coil also in intimate inductive relation with said path primarily for producing an accelerating flux

15

which links said path, said coils being in bucking relation with respect to voltages induced by flux which links the path, means for passing unidirectional current serially through said coils to produce a biasing magnetic field at the locus of said path without producing a corresponding flux centrally linking said path, means for sinusoidally varying the excitation of said coils at similar rates during an initial period to accelerate said particles along said path while maintaining them in said path by the action of said guide field, and means for selectively increasing the rate of change of excitation of said second coil with respect to said first coil at a predetermined point in the operating cycle, thereby to prevent un- 15

16

wanted deviation of said particles from said path because of energy losses attributable to radiation.
WILLEM F. WESTENDORP.
